STEAM IRON

Paul J. Kircher, Plainville, Conn., assignor to Landers, Frary & Clark, New Britain, Conn., a corporation of Connecticut

Application March 10, 1953, Serial No. 341,436

2 Claims. (Cl. 38—77).

This invention relates in general to steam irons and pertains more particularly to a steam iron of the "flash" variety having a filling opening that is always open to atmosphere.

It is an important disadvantage in steam irons of the flash type that when the filling opening remains uncapped or open, and especially when the opening faces forwardly at an elevation not too far above the reservoir itself, then the back and forth movement of the iron during an ironing operation causes turbulence of the water stored within the reservoir of the iron, such splashing about resulting in water passing up through the filling passage and spilling out through the entrance or opening of such passage.

Obviously, such a condition is objectionable and accordingly one purpose of the invention is to obviate any such happening by employing a highly effective baffle means that will not interfere with the filling or emptying of the iron but which will restrict the escape of the water from within the reservoir back through the filling opening.

Another purpose of the invention is to provide a baffle requiring no fastening means that would necessitate physically attaching or connecting the baffle to other parts of the iron. In this respect, it is an aim of the invention to facilitate the assembly of said baffle without noticeably adding to the time and effort that would be required if no baffle were utilized.

A further purpose of the invention is to provide a baffle that need not be cut to any exact length, it being within the contemplation of the invention to employ a coil spring which may in each instance be cut sufficiently long so that in assembling the parts the baffle will be slightly compressed, thereby not only avoiding any mechanical interference that might arise if the baffle were of a non-conformable construction but additionally eliminating any tendency for the baffle to rattle once the iron has been assembled.

A still further object of the invention is to provide a baffle that is exceedingly simple in construction and one which is very inexpensive to manufacture, actually being readily available as standard stock and therefore procurable on the open market.

Other objects will be in part obvious, and in part pointed out more in detail hereinafter.

The invention accordingly consists in the features of construction, combination of elements and arrangements of parts which will be exemplified in the construction hereafter set forth and the scope of the application of which will be indicated in the appended claims.

In the drawings:

Figure 1 is an elevational view of the steam iron, parts of which have been removed to show the interior construction thereof, and

Figure 2 is a sectional view taken in the direction of line 2—2 of Figure 1.

Referring in detail to the drawing, the flash type steam iron selected for the purpose of illustrating the invention

2

has been designated in its entirety by the reference numeral 10, the iron having a soleplate 12 equipped with a steam generating chamber, passages and exit ports through which the steam is extravasated onto the fabric to be ironed. In heat transfer relationship with the steam chamber and ironing face is an electric heating element, preferably embedded within the metal constituting the soleplate. Soleplates of the foregoing character are well known and, therefore, it is not thought necessary to describe and illustrate the referred to soleplate construction in detail.

A tubular post 13 has its lower end anchored to the soleplate 12 and abuts the underside of a shell or casing 14 at its upper end, thereby to aid in supporting said shell in a slightly spaced condition relative to the soleplate for the purpose of minimizing heat transfer from said soleplate thereto. A screw 16 is pictured as holding the shell in fixed relation to the soleplate. Bracket means (not shown) are used to support the rear portion of the shell in a somewhat similar fashion.

While not a part of the invention, an appropriate thermostatic device having a vertical spindle or shaft 18 extends upwardly therefrom, and has attached thereto an arm 20 by which the thermostat may be adjusted to the desired ironing temperature.

The water to be used in the generation of steam is stored in a reservoir 22 and for the sake of compactness the post 13 and the spindle 18 are arranged so that they extend through intermediate portions of the reservoir, there being a pair of heat insulating bushings 24 and 26 encircling the post and spindle to minimize the radiation of heat from these members to the water contained in the reservoir. The upper and lower ends of these bushings are, needless to say, in sealing relation with the reservoir 22 to prevent leakage at these regions.

Near the forward end of the reservoir 22 is an upwardly directed sleeve 28 having its lower end expanded and flared into tight engagement with the top wall of the reservoir. Associated with the sleeve 28 is a somewhat L-shaped filler member 30 containing a passage 32 extending completely therethrough composed of a horizontal section 34 having an entrance or opening at 36 and a vertical section 38 through which water may be introduced to the reservoir. The vertical passage section 38 is of such size as to fit snugly about the sleeve 28, and the filler member 30 in this way receives the major part of its support from said sleeve. A resilient clip 40, however, does supply some retaining action, one end of said clip 40 being made fast with respect to the shell 14 by reason of the screw 16, already alluded to.

A valve mechanism, indicated generally by the numeral 42, serves to permit the downward flow of water from the reservoir 22 of the steam generating chamber, the valve mechanism including an opening 44 through which the water gravitationally enters the valve and a valve stem or rod 46 by which the valve mechanism may be opened and closed. The valve stem or rod 46 is reciprocable in an up and down direction through the vertical section 38 of the passage 32.

Biassing the valve stem 46 upwardly is a coil spring 48, such action causing the valve mechanism 44 to be in an open condition, thereby permitting gravitational discharge of the water within the reservoir 22 to the steam chamber therebelow. In order to close the valve 44, an actuator designated generally by the reference numeral 50 is employed, which actuator merely overcomes, when manipulated by the user, the upward or opening bias of the coil spring 48. The actuator 50 is encased within a hollow handle 52, use of which is made in lifting and guiding the iron 10 through the various motions necessary in carrying out ironing operations. In-

asmuch as the present actuator 50 is fully illustrated and described in my co-pending application entitled "Indicator for Flatiron Control Means," Serial No. 215,318, filed March 13, 1951, now Patent No. 2,642,027, issued on June 16, 1953, further details thereof are not believed needed at this time.

Coming now to the crux of the invention, it will be observed that a coil or helical spring 54 is circumscribed about the valve stem 46, having its upper region received within the cylindrical confines of the sleeve 28. In the illustrated embodiment, the lower end of the spring 54 is circumscribed about the valve means 42, thereby preventing this end from shifting relative to the bottom of the reservoir. The wire size of the spring 54, as well as the proximity of the adjacent turns, influence the baffle effect produced by the spring and from actual tests a stainless steel spring of approximately 20 gauge and 14 turns per inch has been found to give excellent results.

A practical and efficient baffle, it should be emphasized, is required in conjunction with uncapped or open passages, such as the pictured passage 32, inasmuch as in use the iron is moved back and forth, a sudden stopping in the forward travel of the iron causing the water confined in the reservoir 22 to move forwardly with sufficient turbulence to cause the water to splash up through the passage 32, then spilling out the opening 36. However, with adjacent turns of the coil spring 54 in relatively close proximity with each other it will be apparent that a baffle action is produced which effectually resists any such loss of water. The baffle 54, on the other hand, does not interfere with adding water to or emptying the reservoir whenever necessary, an upending of the iron facilitating this procedure.

Not only is the spring 54 influential in producing the above-noted effect, but owing to the compressibility of the spring 54, its free length can always be made somewhat longer than is actually necessary for any installation, the spring merely yielding to the extent required when the member 30 is lowered into place, since the member 30 is equipped with a curved or arcuate shoulder 56 which abuts the upper end of the spring to compress the spring whatever amount is required to permit proper orientation of said member 30. Also, by always having the free length of the spring slightly longer than is actually needed, it will be appreciated that there is never any likelihood that the spring will be loose and rattle during the life of the iron. Still further, it is to be observed that no auxiliary fastening means is required to anchor the baffle, when it assumes the form of a coil spring as described herein and depicted in the accompanying drawings. Yet another advantage stemming from the use of a coil spring baffle is to be found during the inspection procedure at the factory, as the iron moves down the assembly line, for before the member 30 and handle 52 are attached, the spring 54 will be plainly

visible, this being in contradistinction with any baffle arrangement, such as fins or walls, that would be wholly within the reservoir 22.

I claim:

6. A steam iron comprising a soleplate, a reservoir superimposed above said soleplate and extending longitudinally relative thereto, valve means providing communication between the interior of said reservoir and said soleplate, handle means surmounting said reservoir, a member containing a filler passage leading to said reservoir, said passage including a cylindrical portion forming a permanently open filling opening through which water may be introduced to said reservoir via said passage, and coil means of approximately the same outer diameter as the inner diameter of the cylindrical portion of the filler passage extending from the interior of the passage of the bottom of the reservoir said coil means serving as a baffle to resist escape of water stored in said reservoir back through said passage and out through said opening during an ironing operation involving back and forth movements.
2. A steam iron comprising a soleplate, a reservoir superimposed above said soleplate and extending longitudinally relative thereto, valve means disposed near the forward end of said reservoir providing communication between the interior of said reservoir and said soleplate including a vertically projecting valve stem for adjusting said valve means, handle means surmounting said reservoir, a member containing a passage leading to said reservoir having permanently open substantially horizontal and vertical portions forming a forwardly facing filling opening through which water may be introduced to said reservoir via said passage when the iron is upended, said valve stem passing through the vertical passage portion, a downwardly facing shoulder in the vertical passage portion, and a coil spring of approximately the same diameter as the vertical passage circumscribing said valve stem and having its upper end seated on said shoulder in the vertical passage portion and its lower section extending to the bottom of said reservoir, said coil spring having its adjacent turns sufficiently close together to form a baffle for resisting the escape of water stored in said reservoir back through said passage and out through said opening during an ironing operation involving back and forth movements.
